UNITED STATES PATENT OFFICE.

HARRY DALITZ, OF SEATTLE, WASHINGTON.

SPARK-PLUG TESTER AND TERMINAL.

1,107,498,

Specification of Letters Patent.

Patented Aug. 18, 1914

Application filed April 14, 1913. Serial No. 760,970.

To all whom it may concern:

Be it known that I, HARRY DALITZ, a citizen of the United States of America, and a resident of the city of Seattle, in the county of King and State of Washington, have invented certain new and useful Improvements in Spark-Plug Testers and Terminals, of which the following is a specification.

10 My invention has for a primary object to provide a device of simple construction through the medium of which the electrical current can be caused to pass from the side of the working circuit to the other side 15 thereof without passing between the electrodes of the spark plug.

A further object resides in the provision of a device of this type which is durable, comparatively inexpensive to manufacture, 20 and further, capable of adjustment whereby it can be adjusted to either close or open the short circuit.

Further the invention aims to provide a structure wherein such short circuiting connection is combined with a terminal member for the electrode conducting wire of the spark plug.

Other objects will be set forth as my description progresses and those features of 30 construction, arrangements and combinations of parts on which I desire protection, succinctly defined in my annexed claims.

Referring to the accompanying drawing wherein like numerals of reference indicate 35 like parts throughout: Figure 1 is an elevation of a spark plug provided with my invention, the hand hold or handle member being shown in section. Fig. 2 is a perspective of the terminal member, and Fig. 3 is 40 a perspective of the short circuit closing member.

Referring to the drawing by numerals of reference, 1 indicates a terminal member adapted to be connected to wire 2 of one 45 side of the working circuit, as by pliable edge extensions 3, which latter are bent over the circuit wire and then, if desired, soldered or otherwise held in fixed relation. Member 1 which comprises a flat metallic plate, 50 is conveniently notched, as at 4, for reception of the outer externally screw-threaded end portion of conducting wire 5 of spark plug 6. This conducting wire is provided with the usual champing nut 7 and elec- 55 trode 8, the latter co-operating with an elec-

trode 9 of the outer or conducting shell of the plug.

In providing a connection in shunt with the spark gap of plug 6, I extend member 1 beyond the spark plug and provide in such 60 projecting end portion a seat, conveniently comprising alining apertures 10. In this seat a metallic conducting member 11 is slidably mounted. As now considered, conducting member 11 is curved so that when 65 shifted downwardly, its lower end portion 12, which is preferably curved to provide a comparatively broad bearing surface, will make contact with the outer shell of the spark plug. A spring leaf 13 is fixed for 70 movement with member 11 through openings 10 and this, through its tendency to spring from the conducting member 11, is frictionally held in its adjusted position. Spring leaf 13 can, if desired, be formed in- 75 integral with conducting member 11 and desirably has its free end portion turned outwardly to provide a stop 14 for limiting its upward movement. The upper end portion of member 11 is provided with a hand hold 80 or handle 15, of insulating material, the same being provided with an annular guard flange 16 for the tip portions of the fingers and preferably having screw-threaded en- 85 gagement with the conducting member 11 shank extension 18. In my present con- 90 struction, I have shown the lower aperture 10 provided in the turned under end por- 95 tion 1' of terminal member 1.

In practice, the conducting member 11 will 90 normally be elevated, as shown in Fig. 1. From this position it can be lowered, being slid through openings 10, to test the strength of the current, it, at such time, being ad- 95 justed to vary the spacing of its end portion 12 with respect to shell of plug 6, as will be readily understood. For detecting a foul plug or one which is not sparking properly in an engine having two or more cylinders, the operation would be as follows: The sev- 100 eral spark plugs of the cylinders are allowed to each, in turn, be connected in the working circuit while the remaining spark plugs are short circuited through the closing of their conducting switch members. Thus, each 105 spark plug can be individually tested as to its proper operation without removing the same from the cylinder.

Having thus described my invention what I claim as new, and desire to secure by Let- 110

ters Patent of the United States of America, is:—

1. A device of the character described comprising a terminal member consisting of a plate adapted to be mounted on a spark plug and having an extension projecting beyond the latter, said extension having a seat formed therein, and a conducting member slidably engaged in the seat of the terminal member and being of curved formation whereby on sliding the conducting member the contacting portion thereof will move inwardly to engage the plug.
2. A device of the character described comprising a terminal member consisting of a plate having an extension formed with a seat, a conducting member slidably engaged in the seat of said terminal member for short circuiting the spark plug, and a resilient element integral with said conducting member for holding the same in its adjusted position.
3. A device of the character described comprising a terminal member consisting of a plate having an extension formed with a seat, a conducting member slidably engaged in the seat of said terminal member for short circuiting the spark plug, and a resilient element carried by said conducting member for holding the same in its adjusted position.

4. A device of the character described comprising a terminal member having one end portion turned back and provided therein together with said end portion with alining apertures, and a conducting member for 35 short circuiting the spark plug, said conducting member being slidably engaged in the apertures of the terminal member and curved inwardly to engage the spark plug on 40 sliding said conducting member.

5. A device of the character described comprising a terminal member having one end portion turned back and provided therein together with said end portion with alining apertures, a conducting member for 45 short circuiting the spark plug, said conducting member being slidably engaged in the apertures of the terminal member and curved inwardly to engage the spark plug on 50 sliding said conducting member, and a resilient element carried by said conducting member and engaging in the apertures of the terminal member for holding the conducting member in adjusted positions.

Signed at Seattle, Washington this 1st day 55 of March 1913.

HARRY DALITZ.
